SWITCH CONTROL AND INDICATION
SYSTEM

Henry S. Young, Wilkinsburg, Pa., assignor to
The Union Switch & Signal Company, Swiss-
vale, Pa., a corporation of Pennsylvania

Application August 17, 1938, Serial No. 225,413

21 Claims. (Cl. 246—219)

My invention relates to a system for securing over a pair of control wires and a common wire remote control of a motor for operating a railway switch, and for also securing at the control point over the same wires an indication of the position of the switch.

It is an object of my invention to provide a system of the type described which employs neutral control and indication circuits.

10 A further object of my invention is to provide a system of the type described and which will eliminate the necessity for a split battery.

Another object of my invention is to provide a system of the type described which incorporates means located in the vicinity of the switch for preventing storage of switch control.

15 A further object of my invention is to provide an improved switch control and indication system.

20 Other objects of my invention and features of novelty will be apparent from the following description taken in connection with the accompanying drawing.

I shall describe one form of apparatus embodying my invention, together with a modification which I may employ, and shall then point out the novel features in the claims.

25 In the drawing, Fig. 1 is a diagram illustrating a system embodying my invention, and Fig. 2 is a fragmentary diagram illustrating a modification of the system shown in Fig. 1.

Similar reference characters refer to similar parts in both views.

30 Referring to Fig. 1 of the drawing, the reference character W designates a railway track switch which is operated between a normal and a reverse position by means of a motor M. The motor M is controlled by a normal switch control relay NWR and a reverse switch control relay RWR in such manner that the motor M is caused to operate the switch W to its normal position when the relay NWR is energized and the relay RWR is deenergized, while the motor is caused to operate the switch W to its reverse position when the relay RWR is energized and the relay NWR is deenergized.

35 The relays NWR and RWR are controlled by a polarized switch repeating relay WP, a slow release neutral relay WRP and a lock relay LR in a manner hereinafter described in detail.

40 The switch repeating relay WP is controlled by contacts 10 and 11 which are operatively associated with the switch W so as to be actuated to

one position or another according as the switch occupies its normal or reverse position.

The switch contact 10 is constantly connected by a wire 14 to one terminal B of a battery 15 located in the vicinity of the switch W, while the 5 switch contact 11 is constantly connected by a wire 16 to a terminal C of the battery 15.

When the switch W is in the normal position, the contact 10 engages a stationary contact which is connected by a wire 18 to one terminal 10 of the winding of the relay WP, while in this position of the switch W the contact 11 engages a stationary contact which is connected by a wire 19 to the other terminal of the winding of the relay WP with the result that the winding of the 15 relay WP is energized with current of one relative polarity supplied from the battery 15, and the polar contact 20 of the relay WP, as well as the other polar contacts of this relay, is caused to assume its normal position as shown in the 20 drawing.

Similarly, when the switch W is in the reverse position, the contact 10 engages a stationary contact which is connected by the wire 19 to a terminal 25 of the winding of the relay WP, while in this position of the switch W the contact 11 engages a stationary contact which is connected by the wire 18 to a terminal of the winding of relay WP with the result that the winding of the 30 relay WP is energized with current of the opposite relative polarity supplied from battery 15 and the polar contact 20 of relay WP is caused to move to its reverse position.

The polar contact 20 of relay WP is connected by a wire 24 to terminal C of a battery 25 located 35 at a point remote from the switch, such as at an interlocking tower from which it is desired to control the switch W. The wire 24 may be a common wire which is employed in circuits other than the switch control and indication circuits 40 illustrated in this application.

The polar contact 20 when in its normal position as shown in the drawing engages a contact 28 which is connected by a wire 39 to one terminal of the winding of the relay NWR. The polar 45 contact 20 when in its reverse position engages a stationary contact 32 which is connected by a wire 33 to a terminal of the winding of the relay RWR.

It will be seen, therefore, that when the switch 50 W is in the normal position, the winding of relay WP is energized with current of one relative polarity, and the polar contact 20 of relay WP operates to establish a circuit from common wire 24, and thereby from terminal C of battery 25, 55

to wire 30 leading to a terminal of the winding of the relay NWR. Similarly, when the switch W is in the reverse position, the polar contact 20 of relay WP establishes a circuit from wire 24 to the wire 33 leading to a terminal of the winding of relay RWR.

A branch of the wire 30 is connected to a stationary contact 35 of relay WRP. The contact 35 is engaged by a movable contact 36 when the relay winding is energized, while the contact 36 has connected thereto a branch of wire 33.

It will be seen, therefore, that when the contact 36 of relay WRP is picked up, a circuit is established between wires 30 and 33 with the result that regardless of whether the contact 20 of relay WP operates to establish a circuit from the common wire 24 to either wire 30 or to wire 33, a circuit is also established from wire 24 to the other of these wires over the contact 36 of relay WRP.

One terminal of the winding of the relay WRP is constantly connected by a branch of wire 16 to terminal C of the battery 15, while the other terminal of the winding of this relay is connected by a wire 40 to a stationary contact 41 of relay NWR and to a stationary contact 42 of relay RWR. The relay NWR has a movable contact 43 which when picked up engages a stationary contact 41, while the relay RWR has a movable contact 44 which when picked up engages the stationary contact 42. The contacts 43 and 44 are connected by branches of wire 39 to a contact 45 which when the lock relay LR is energized is engaged by a contact 92 to which is connected wire 14 leading to terminal B of the battery 15. It will be seen, therefore, that the winding of relay WRP will be energized when the contacts of either of the relays RWR and NWR are picked up, providing the contact 92 of the lock relay is picked up, and will be deenergized when the contacts of both relays RWR and NWR are released or when the contact of the lock relay is released.

This system includes means located at the point from which it is desired to control the switch W and operable to selectively energize the switch control relays NWR and RWR to thereby effect operation of the motor M to move the switch from one position to the other.

At the control point there is located a switch control lever L which is movable between a normal and a reverse position. Associated with the lever L are contacts 46 and 47 which are movable with the lever. The contact 46 has connected thereto a control wire 50 leading to a movable contact 51 of relay RWR, while the contact 47 has connected thereto a control wire 52 leading to a movable contact 53 of relay NWR.

In the normal position of the lever L the contact 46 engages a stationary contact 55 which is connected by a wire 56 to a terminal of the winding of relay LKR, the other terminal of which is connected by a wire 58 to terminal B of the battery 25. In the normal position of the lever L the contact 47 engages a stationary contact 60 which is connected by a wire 61 to a terminal of the winding of the relay WKR, the other terminal of which is connected by wire 62 to the terminal C of battery 25.

In the reverse position of the lever L the contact 46 engages a stationary contact 64 to which is connected a branch of wire 61, while the contact 47 engages a stationary contact 65 to which is connected a branch of wire 56.

The relay LKR has a movable contact 66 which

when picked up engages a stationary contact which is connected to one terminal of the transit light TL, the other terminal of which is connected by wire 62 to terminal C of battery 25. The contact 66 when released engages a stationary contact which is connected to one terminal of the lock light LL, the other terminal of which is connected by wire 62 to terminal C of battery 25.

The contact 66 is connected by a wire 68 to contact 69 of relay WKR, while contact 69 when released engages a stationary contact 70 to which is connected a branch of wire 58 leading from terminal B of the battery 25.

The contact 51 of relay RWR to which is connected control wire 50 engages, when picked up, stationary contact 72 which is connected by a wire 73 to reverse polar contact 74 of polarized switch control relay WP.

The contact 51 of relay RWR when released engages stationary contact 76 which is connected to movable contact 77 of lock relay LR, while the contact 77 when picked up engages a stationary contact 78 which is connected by a wire 79 to one terminal of the switch control relay NWR, the other terminal of which has connected thereto the wire 30 leading to normal polar contact 28 of polarized switch control relay WP.

The contact 53 of relay NWR, to which is connected control wire 52, when picked up engages a stationary contact 81 which is connected by a wire 82 to a normal polar contact 83 of polarized switch control relay WP. The contact 53 when released engages a stationary contact 85 which is connected by a wire 86 to a contact 87 of relay LR. The contact 87 is engaged by a movable contact 89 of relay LR when the contact 89 is picked up, while the contact 89 is connected by a wire 90 to one terminal of the winding of the relay RWR.

The lock relay LR is provided with a winding, while the circuit for energizing this winding is controlled in the well-known manner by means responsive to traffic conditions in the vicinity of the switch W so that the relay winding is energized only when it is safe to effect movement of the switch W between its two positions, and is deenergized at all other times.

The details of the system for controlling the circuit of the winding of the lock relay LR form no part of my invention, and one form of control system for the circuit of this winding which I may employ is shown in United States Patent No. 1,959,072 to Herbert A. Wallace.

The lock relay LR has a contact 92 to which is connected a branch of the wire 14 leading from terminal B of battery 15, while the contact 92 when released engages a stationary contact 93 which is connected by a wire 94 to a stationary contact 95 associated with the relay WP. As previously pointed out the contact 92 of the lock relay LR when picked up engages contact 45 to which is connected wire 39 leading to the contacts 43 and 44 of relays NWR and RWR.

The polarized switch control relay WP has a neutral contact 96 which when picked up engages the contact 95, while the contact 96 is connected to a polar contact 97.

The polar contact 97 when in its normal position, as shown in the drawing, engages a stationary contact 98 which is connected by a wire 70 to a switch contact 100. The polar contact 97 when in its reverse position engages a stationary contact 102 which is connected by a wire 104 to a switch contact 106.

In all positions of the switch W except the

normal position thereof the switch contact 100 engages a stationary contact 108, while the contact 108 has connected thereto a branch of the wire 79 which is connected to one terminal of the winding of the relay NWR. 5

Likewise the switch contact 106 in all positions of the switch W except the reverse position thereof engages a stationary contact 110 which has connected thereto a branch of the wire 90 which is connected to one terminal of the winding of the relay RWR. 10

The switch W also has associated therewith contacts 114 and 115 which control the energizing circuits of the motor M. The contacts 114 and 115 are connected by a wire 116 to one terminal of the field winding 118 of the motor M, while the other terminal of the field winding 118 has connected thereto a branch of the wire 16 leading from the terminal C of the battery 15. 15

The contact 114 engages a stationary contact 120 in all positions of the switch W except the normal position thereof, while the contact 115 engages a stationary contact 121 in all positions of the switch W except the reverse position 20 thereof. 25

The contact 120 is connected by a wire 123 to a stationary contact 124 which is engaged by a movable contact 125 of the relay RWR when the relay winding is deenergized. When the winding of relay RWR is energized, the contact 125 is picked up and it engages a stationary contact 126 to which is connected a branch of the wire 14 leading from terminal B of battery 15. 30

The contact 125 of relay RWR is constantly connected to one of the brushes 128 associated with the armature 130 of motor M. 35

The contact 121 is constantly connected by a wire 132 to a stationary contact 133 associated with the relay NWR. The contact 133 is engaged by a movable contact 134 of relay NWR when the contact 134 is released, while the contact 134 is connected by a wire to brush 135 associated with the armature 130 of motor M. 40

The contact 134 of relay NWR when picked up engages a stationary contact 136 which has connected thereto a branch of wire 14 leading to terminal B of the battery 15. 45

The construction of the system having been described, its operation will now be explained. The system is shown in the drawing with the 50 various parts of the apparatus in the positions which they assume when the switch W is in the normal position, the control lever L is also in the normal position, and the lock relay LR is 55 energized.

As the switch W is in the normal position the switch contacts 10 and 11 operate to establish a circuit to energize the winding of the relay WP with current of the normal polarity with the 60 result that the neutral contacts 85 and 96 of relay WP are picked up, while the polar contacts 20, 84 and 97 are in their normal positions as shown. 65

At this time the winding of switch control relay NWR is energized over a circuit which is traced from terminal B of battery 25 through wire 58, winding of relay LKR, wire 56, contacts 55-46, wire 50, contacts 51-76 of relay RWR, contacts 77-78 of relay LR, wire 79, winding of relay 70 NWR, wire 30, normal polar contacts 28-20 of relay WP and common wire 24 to terminal C of battery 25. 75

At this time the winding of relay RWR is de-energized since the contact 53 of switch control 75 relay NWR is picked up, thereby interrupting

connection from wire 52 to contact 85, and since polar contact 97 of switch repeating relay WP is in its normal position, thereby interrupting connection with wire 104 which is also connected to wire 90 leading to the terminal of the winding 5 of relay RWR.

As the contacts of relay NWR are picked up contact 43 engages contact 41 and completes a circuit from wire 39 leading from contact 45 of lock relay LR to wire 40 leading to a terminal 10 of the winding of the relay WRP, the other terminal of which is connected by wire 16 to terminal C of the battery 15. At this time the contact 92 of lock relay LR is assumed to be picked up and accordingly the winding of the relay WRP 15 is energized and the contact 36 is picked up and establishes a circuit from wire 30 to wire 33 leading to the terminal of the winding of the relay RWR, and to the normal polar contact 32 of relay WP. The winding of relay RWR, however, 20 remains deenergized since contact 53 of relay NWR is picked up and polar contact 97 of relay WP is in the normal position. 25

At this time as the contacts of relay NWR are picked up contact 134 engages stationary contact 136 to establish a circuit from terminal B of battery 15 to the brush 135 of the motor M. Likewise, as the contacts of relay RWR are released the contact 125 engages stationary contact 124 to connect brush 128 to wire 123 leading 30 to switch operated contact 120. However, at this time, the switch W being in the normal position, the contact 114 is not in engagement with contact 120 with the result that the circuit for the armature 130 of the switch motor M is interrupted and the motor therefore is not operated. 35

At this time a circuit is established to energize the winding of the relay LKR with current supplied by the battery 25. This circuit is the 40 same as that for relay NWR and is traced from terminal B of battery 25 through wire 58, winding of relay LKR, wire 56, control lever contacts 55-46, control wire 50, contacts 51-76 of relay RWR, contacts 77-78 of relay LR, wire 79, winding of relay NWR, wire 30, normal polar contacts 28-20 of relay WP, and wire 24 to terminal C of battery 25. As the winding of the relay LKR is energized the contact 66 thereof is picked up and establishes a circuit from wire 68 to the terminal 50 of the transit light TL. 45

In addition, when the control lever L and the switch W are in correspondence, a circuit is established to energize the winding of relay WKR with current supplied from battery 15. This circuit is traced from terminal B of battery 15 through wire 14, neutral contacts 88-85 and polar contacts 84-83 of switch repeating relay WP, wire 82, contacts 81-53 of relay NWR, control wire 52, control lever contacts 47-60, wire 60 61, winding of relay WKR, wire 62 to common wire 24, and thence to wire 16 and terminal C of battery 15. 55

As the winding of relay WKR is energized the contact 69 of this relay is picked up, thereby 65 interrupting the circuit to the transit light TL, while the circuit of the lock light LL is additionally interrupted since the contact 66 of relay LKR is picked up.

At this time, therefore, the lamps TL and LL 70 are both deenergized to thereby indicate that the switch W and the control lever L are in correspondence and that the switch is not locked.

If at this time the operator wishes to move the switch W from the normal position to the 75

reverse position, he may do so by moving the lever L from its normal to its reverse position.

As a result of this movement of the control lever L the previously traced circuits for energizing the relays NWR, LKR and WKR will be interrupted, while a circuit will be established to energize the winding of the relay RWR.

On deenergization of the winding of relay NWR its contact 41 is released, thereby interrupting the circuit for energizing the winding of the relay WRP. On interruption of the energizing circuit of the winding of relay WRP the contact 36 of this relay does not release instantaneously, however, since the relay WRP is of the slow release type. As a result the contact 36 will be maintained picked up for a short time interval and will continue to establish connection between wire 39 leading from the normal polar contact 28 of relay WP to the wire 33 leading to a terminal of the winding of the relay RWR.

On movement of the switch lever L to the reverse position its contact 47 engages contact 65 and thereby establishes a circuit from terminal B of the battery 25 to control wire 52, this circuit including wire 58, winding of relay LKR, wire 56 and contacts 65-47. At this time contact 53 of relay NWR is released and engages stationary contact 85 so that on completion of a circuit from terminal B of battery 25 to control wire 52, a circuit is completed through contacts 53-85 of relay NWR, wire 86, contacts 87-89 of lock relay LR to wire 90 leading to a terminal of the winding of relay RWR. At this time the other terminal of the winding of relay RWR is connected to terminal C of the battery 25 by means of a circuit which includes wire 33, contacts 36-35 of relay WRP, wire 30, normal polar contacts 28-20 of relay WP and common wire 24.

As the circuit for energizing the relay RWR is complete, the contacts of this relay will pick up and contact 46 will engage stationary contact 42 to again complete the circuit for energizing the winding of the relay WRP with the result that contact 36 of this relay will be maintained picked up and will maintain the circuit for energizing the winding of relay RWR.

On release of the contact of relay NWR the contact 134 engages contact 133 to thereby connect the brush 135 of switch motor M in series with the field winding 118. On picking up of the contacts of relay RWR the contact 125 thereof connects brush 128 of switch motor M to terminal B of the battery 15, and the motor M is now caused to operate to move the switch W from the normal position to the reverse position.

On movement of the switch W the switch contacts 10 and 11 are moved out of engagement with the stationary contacts to which are connected the wires 18 and 19, respectively, thereby deenergizing the winding of the switch control relay WP. However, because of the internal construction of the polarized switch control relay WP, the polar contact 20 thereof remains in engagement with the normal polar contact 28 to thereby maintain the circuit to the winding of the switch control relay RWR.

On movement of the switch W to the reverse position the contact 115 is moved out of engagement with the contact 121, thereby interrupting the circuit for energizing the field winding 118 and the armature 130 of the switch motor M with the result that the switch motor M no longer operates.

In addition, on movement of the switch W to the reverse position the switch contacts 10 and

11 are moved to positions in which the switch contact 10 engages a stationary contact to which is connected a branch of the wire 19, while the switch contact 11 engages a stationary contact to which is connected a branch of the wire 18. Accordingly, the winding of the relay WP is energized with current from the battery 15 of a polarity such as to cause movement of the polar contacts of the relay from their normal to their reverse positions.

On this movement of the polar contact 20, the wire 33 leading from a terminal of the switch control relay RWR is directly connected to the common wire 24, and thereby to the terminal C of battery 25, instead of being connected to wire 24 by way of normal polar contact 28, wire 30 and contacts 35-36 of relay WRP.

On movement of the switch control lever L from the normal to the reverse position the previously traced circuit for energizing the winding of relay LKR is interrupted and another circuit for energizing this relay is established. This circuit is the same as that for energizing the winding of relay RWR and is traced from terminal B of battery 25 through wire 58, winding 25 of relay LKR, wire 56, control lever contacts 65-47, control wire 52, contacts 53-85 of relay NWR, wire 86, contacts 87-89 of relay LR, wire 90, winding of relay RWR, wire 33, contacts 36-35 of relay WRP, wire 30, normal polar contacts 28-20 of relay WP and common wire 24 to terminal B of battery 25.

When the polar contact 20 of relay WP is operated from its normal to its reverse position, the winding of relay LKR continues to be energized over the previously traced circuit, except that instead of connection from wire 33 to common wire 24 being made over contacts 35-36 of relay WRP and normal polar contacts 28-20 of relay WP, this connection is now established by means of the reverse polar contacts 32-20 of relay WP.

It will be seen, therefore, that on movement of the switch control lever L from the normal to the reverse position the relay LKR is maintained energized with the result that the contact 66 remains picked up.

On movement of the switch control lever L from the normal to the reverse position the circuit for energizing the winding of relay WKR is interrupted by opening of the control lever contacts 47-60, and the contact 69 of relay WKR is released and engages contact 70 to thereby establish a circuit from wire 58, leading from terminal B of battery 25, to wire 68 leading to contact 66, which at this time engages the stationary contact which is connected to a terminal of transit light TL. The transit light TL, therefore, will be supplied with energy and will be illuminated to indicate that the switch control lever L and the switch W are out of correspondence.

On movement of the switch control lever L to the reverse position contact 46 engages contact 64 to thereby connect wire 61 leading from the terminal of the winding of relay WKR to control wire 50 which is connected to contact 51 of relay RWR. When the contacts of relay RWR become picked up on energization of the winding of this relay, contact 51 engages contact 72 which is connected by wire 73 to reverse polar contact 74 of switch repeating relay WP.

At the time the switch control lever L is moved to the reverse position the polar contacts of the switch repeating relay WP are in their normal positions, and hence the circuit for energizing 75

the winding of relay WKR is interrupted. On movement of the switch W to the reverse position the polar contacts of the relay WP are caused to move to the reverse position, as previously explained, with the result that polar contact 84 engages contact 74, while the neutral contact 85 of this relay is picked up and a circuit is established from wire 73 to wire 14 which is connected to terminal B of battery 13. The circuit from one terminal of the winding of relay WKR to terminal B of battery 15 is now complete, while the other terminal of winding of relay WKR is connected to terminal C of battery 15 by way of wire 62, common wire 24 and wire 16. The winding of relay WKR, therefore, will be energized as soon as the switch W completes its movement to the reverse position, and on energization of the winding of this relay the contact 69 will become picked up, thereby interrupting the circuit for energizing the transit light TL. This lamp, therefore, will no longer be illuminated and will indicate that the switch control lever L and the switch W are again in correspondence.

A similar sequence of operation takes place when the switch W is in the reverse position and the operator wishes to move it to the normal position. When the switch W is in the reverse position and the control lever L is also in the reverse position, the winding of the relay RWR is energized over the previously traced circuit, while the winding of relay NWR is deenergized. In addition, the switch contacts 10 and 11 operate to supply current of reverse polarity to the winding of the relay WP with the result that the polar contacts of this relay occupy their reverse positions, while the neutral contacts of the relay are picked up.

Furthermore, as the contacts of relay RWR are picked up, the contact 44 establishes a circuit to energize the winding of relay WRP with the result that its contact 36 is picked up and establishes a connection between wire 33 and wire 30.

On movement of the switch control lever L from the reverse position to the normal position the previously traced circuit for energizing the winding of relay WKR is interrupted due to disengagement of control lever contact 46 from contact 64 with the result that contact 69 of relay WKR is released and establishes a circuit to light transit light TL to indicate that the control lever L and the switch W are out of correspondence.

In addition, upon movement of the control lever L from the reverse to the normal position contact 47 is moved out of engagement with contact 65, thereby interrupting the circuit for energizing the winding of relay RWR. On deenergization of the winding of relay RWR the contacts of this relay release and contact 44 interrupts the energizing circuit for the winding of the slow release relay WRP, but, as previously explained, contact 36 of relay WRP does not release instantaneously.

On movement of the switch control lever L from the reverse to the normal position contact 46 is moved into engagement with the contact 55 to thereby complete a circuit for energizing the winding of the relay NWR. This circuit is traced from terminal B of battery 25 through wire 58, winding of relay LKR, wire 56, contacts 55-46 of control lever L, control wire 50, contact 51-76 of relay RWR, contacts 77-78 of lock relay LR, wire 79, winding of relay NWR, wire 30, contacts 35-36 of relay WRP, wire 33,

reverse polar contacts 32-20 of relay WP, and common wire 24 to terminal C of battery 25.

As the contacts of relay NWR are picked up and as the contacts of relay RWR are released, circuits are established to energize the switch motor M to cause it to operate in a direction to move the switch from the reverse to the normal position. The energizing circuit for the motor M is interrupted on movement of the switch W to the normal position by movement of contact 114 out of engagement with contact 120.

On picking up of the contacts of relay NWR, contact 43 establishes a circuit from wire 39 to wire 40 leading to a terminal of the winding of relay WRP. This winding is energized, therefore, and contact 36 is maintained picked up to maintain connection between wires 33 and 30, and thus maintain the energizing circuit for the winding of relay NWR.

On movement of the switch control lever L to the normal position the winding of relay LKR is energized in series with the winding of the relay NWR over the circuit traced in detail in connection with relay NWR, and as the winding of relay LKR is energized, its contact 66 remains picked up.

On movement of the switch W from the reverse to the normal position the switch operated contacts 10 and 11 operate to again supply current of normal polarity to the winding of the relay WP with the result that the polar contacts of this relay are caused to move from their reverse to their normal positions.

On this movement of the polar contacts of relay WP a circuit is established to again energize the winding of relay WKR. This circuit is traced from terminal B of battery 15 through wire 14, neutral contacts 88-85 and polar contacts 84-83 of relay WP, wire 82, contacts 81-53 of relay NWR, control wire 52, switch lever contacts 47-60, wire 61, winding of relay WKR, wire 62 to common wire 24 and thence to wire 16 and terminal C of battery 15. On energization of the winding of the relay WKR the contact 69 thereof becomes picked up, thereby interrupting the circuit for energizing the transit light TL, which thereupon becomes extinguished to indicate that the switch W and the switch lever L are again in correspondence.

On movement of the polar contact 20 of the switch repeating relay WP from the reverse to the normal position a circuit is established to connect wire 30, leading from a terminal of the winding of relay NWR, directly to the common wire 24 instead of over the wire 33 and the contacts 36-35 of relay WRP. Accordingly, on movement of the polar contacts of relay WP from their reverse to the normal positions the circuit for energizing the winding of relay NWR is maintained and the contacts of this relay are maintained picked up.

The system provided by this invention is arranged so that the position of the switch W cannot be changed when the lock relay LR is deenergized. The system is also arranged so that when the lock relay LR is deenergized, the lock light LL is lighted to indicate that the switch W cannot be operated.

When the winding of the lock relay LR is deenergized, the contact 71 of the relay LR no longer engages contact 78 and thereby interrupts the energizing circuit for the winding of the relay NWR with the result that the winding of relay NWR cannot be energized. Similarly, when the winding of relay LR is deenergized, the contact 89 is released, thereby interrupting the circuit for

the winding of the relay RWR with the result that the contacts of this relay are released.

When the contacts of both the relays RWR and NWR are released, no current can be supplied from the battery 15 to operate the switch motor M and the motor, therefore, cannot move the switch W.

When the lock relay LR is energized, the winding of the relay LKR is connected in series with the winding of one or the other of the switch control relays RWR or NWR depending upon the position of the switch control lever L. However, since the circuits for energizing the windings of these relays are both interrupted at a time when the lock relay LR is deenergized, the winding of the relay LKR will also be deenergized and its contact 66 will be released and will engage a stationary contact which is connected to one terminal of the lock light LL.

It will be seen also that when the lock relay LR is deenergized, the energizing circuit of the relay WKR will also be interrupted. If the switch control lever L is in the normal position, as shown in the drawing, so that the contact 47 engages the contact 60 and connects wire 61 to control wire 52, the energizing circuit of the winding of relay WKR will be interrupted since contact 53 of relay NWR is released and engages contact 85 to which is connected wire 86 leading to contact 87 which at this time is not engaged by contact 89 of lock relay LR.

Similarly, if the control lever L is in its reverse position so that contact 46 engages contact 64 to connect wire 61 to control wire 50, the circuit of the winding of relay WKR will also be deenergized. This will be true because wire 50 is connected to contact 51 of relay RWR which at this time is released and engages contact 76 which is connected to contact 77 of lock relay LR, which contact is released, thereby interrupting the circuit.

It will be seen, therefore, that regardless of the position of the switch control lever L, when lock relay LR is released the winding of relay WKR will be deenergized and contact 69 of relay WKR will be released and will engage contact 70 and thus connect terminal B of battery 25 to wire 68 which is connected by contact 66 of relay LKR to lock lamp LL, which lamp will be illuminated to indicate that the switch W is locked and cannot be operated from the position which it occupies.

The system provided by this invention is arranged so that if the switch W should creep, that is, if it should move from either its normal or reverse position, the switch motor M will be energized so as to return the switch W to the position which the switch should occupy, and so that the motor will be energized even though the lock relay LR is deenergized.

When the lock relay LR is energized, one or the other of the switch control relays RWR or NWR will be energized depending upon the position of the switch control lever L.

If the normal switch control relay NWR is energized, contact 134 will be picked up and will establish a circuit from wire 14, leading from terminal B of battery 15, to brush 135 of the switch motor M, while the energizing circuit for the switch motor will be complete as soon as the switch W has moved far enough away from the normal position to cause switch operated contact 114 to engage contact 120. When contact 114 engages contact 120, switch motor M will be energized and will drive the switch to the normal position, thereby moving contact 114 out of engagement with contact 120 and again interrupting the energizing circuit for the switch motor M.

Similarly, if the switch W creeps at a time when the reverse switch control relay RWR is energized, at which time contact 125 is picked up and connects wire 14, leading from terminal B of battery 15, to brush 128 of switch motor M, then when the switch W moves far enough away from the reverse position to cause contact 115 to engage contact 121, the motor will be operated to return the switch to the reverse position.

It will be seen, therefore, that when the lock relay LR is energized, at which time one or the other of the switch control relays NWR and RWR is energized, the switch motor M will be energized to effect movement of the switch W back to its initial position if the switch should creep therefrom.

The system is also arranged so that if at a time when the lock relay LR is deenergized, at which time neither of the switch control relays RWR and NWR is energized, as explained in detail above, the switch W should creep from either its normal or reverse position, the proper one of the switch control relays RWR or NWR will be energized to thereby complete the energizing circuit for the switch motor M and cause it to effect movement of the switch W to the position which it should occupy.

When the switch W is in the normal position, the switch operated contacts 10 and 11 operate to establish circuits to energize the winding of the switch repeating relay WP in the normal direction with the result that the polar contacts of this relay are in their normal positions as shown in the drawing.

If at such time the switch W should creep from the normal position, the switch operated contact 100 will engage the stationary contact 108 and thereby complete a circuit from wire 99, leading from normal polar contact 98, to contact 108 to which is connected a branch of wire 79 leading to the terminal of the winding of relay NWR. The various parts of the apparatus are arranged and proportioned so that the contact 100 will engage contact 108 before contacts 10 and 11 are moved out of engagement with the stationary contacts which they engage in the normal position of the switch. Accordingly, at the time when contact 100 engages contact 108 the winding of relay WP will be energized and the neutral contact 96 thereof will be picked up and will establish a circuit from wire 94 to polar contact 97 which engages the normal polar contact 98. Since it is assumed at this time that the lock relay LR is deenergized its contact 92 is released and engages contact 93 to connect wire 14 leading from terminal B of battery 15 to wire 94. Accordingly, a circuit is established from terminal B of battery 15 to wire 79, and the winding of relay NWR is energized over a circuit which is traced from terminal B of battery 15 through wire 14, contacts 92-93 of relay LR, wire 94, contacts 95-96 of relay WP, normal polar contacts 97-98 of relay WP, wire 99, switch contacts 100-108, wire 79, winding of relay NWR, wire 30, and the normal polar contacts 28-20 of relay WP to which is connected wire 16 leading from terminal C of battery 15.

On energization of the winding of relay NWR its contact 134 is picked up, thereby establishing a circuit from wire 14 leading from terminal B of battery 15 to brush 135 of the switch motor M. Since it is assumed that the switch W has crept away from the normal position, the switch op-

erated contact 114 will be in engagement with the contact 120 to thereby complete the energizing circuit for the switch motor M and the motor M will be operated in a direction to return the switch W to the normal position.

As soon as the switch has reached the normal position, the contact 114 will be moved out of engagement with the contact 120, thereby interrupting the energizing circuit for the switch motor M with the result that the motor will cease to operate.

Likewise, on the return of the switch W to the normal position the contact 100 is moved out of engagement with the contact 108, thereby interrupting the previously traced circuit for energizing the winding of relay NWR with the result that this winding is deenergized and the relay contacts become released.

In similar manner, if the switch W is in the reverse position and should creep therefrom at a time when the lock relay LR is released, the switch control relay RWR will be energized to complete the energizing circuit for the switch motor M and cause the motor to return the switch to the reverse position.

At a time when the switch is in the reverse position, the switch operated contacts 10 and 11 establish circuits to supply current of reverse polarity to the winding of the switch repeating relay WP with the result that the polar contacts of this relay are in their reverse positions, while the neutral contacts of the relay are picked up.

As previously explained, the various parts of the apparatus are arranged and proportioned so that in the reverse position of the switch W, the switch operated contacts 10 and 11 will remain in engagement with the stationary contacts associated therewith until after the switch operated contact 106 has been moved into engagement with stationary contact 110.

If at a time when the switch is in the reverse position it should creep therefrom, the contact 106 will be moved into engagement with contact 110 to thereby establish a circuit from wire 104 to wire 90 leading to a terminal of the winding of relay RWR. The winding of relay RWR will thereupon become energized by current supplied over a circuit which is traced from terminal B of battery 15 through wire 14, contacts 92-93 of relay LR, wire 94, neutral contacts 95-96 of relay WP, reverse polar contacts 97-102 of relay WP, wire 104, switch contacts 106-110, wire 90, winding of relay RWR, wire 33 and reverse polar contacts 32-20 of relay WP to wire 16 leading to terminal C of battery 15.

On energization of the winding of relay RWR its contact 125 will be picked up and will connect wire 14 to brush 123 of switch motor M. As the switch W is assumed to have crept from the reverse position, the contact 115 will engage contact 121 and complete the energizing circuit for the switch motor M and the motor will operate to return the switch to the reverse position.

When the switch W reaches the reverse position, the contact 115 is moved out of engagement with contact 121, thereby interrupting the energizing circuit for the switch motor M with the result that the motor ceases to operate.

Similarly, when the switch W attains the reverse position, contact 106 is moved out of engagement with the contact 110, thereby interrupting the energizing circuit for the winding of reverse switch control relay RWR with the result that the winding becomes deenergized and its contact 125 is released.

The system provided by this invention is arranged so that if the position of the switch control lever L is changed at a time when the lock relay LR is deenergized, no change will occur in the position of the switch W on subsequent energization of the lock relay LR. As previously explained, when the lock relay LR is deenergized, the circuits for energizing the relays NWR and RWR are interrupted so that neither relay can be energized. Since the contacts of relays RWR and NWR are both released, the energizing circuit for the winding of relay WRP is interrupted and the contact 36 of this relay is released, thereby interrupting connection between the wires 30 and 33.

When the switch W is in the normal position, the switch operated contacts 10 and 11 establish a circuit to energize the winding of the relay WP in the normal direction and the polar contacts of this relay will be in their normal positions as shown in the drawing. If at this time the lock relay LR is deenergized and the switch control lever L is moved from its normal to its reverse position, the relay RWR will not become energized on subsequent energization of the winding of lock relay LR.

Thus it will be seen that when the switch control lever L is in the reverse position, its contact 41 engages stationary contact 65 to thereby establish a circuit from wire 56, leading from terminal B of battery 25, to control wire 52. At this time the contacts of relay NWR are released and contact 53 connects control wire 52 to wire 86, while on picking up of contact 69 of relay LR wire 86 is connected to wire 90 leading to a terminal of winding RWR. However, it will be seen that no circuit is established to connect wire 33, leading from the other terminal of the winding of relay RWR, to the common wire 24 and thereby to terminal C of battery 25. This is true since polar contact 20 of relay WP is in its normal position and therefore out of engagement with reverse polar contact 32 to which is connected wire 33, while the contact 36 of relay WRP is released so that it does not establish a circuit between wires 30 and 33. Accordingly, when the contacts of relay LR become picked up, the circuit for energizing the winding of relay RWR remains interrupted and the contacts of this relay remain released, while the energizing circuit for the switch motor M remains deenergized, and the motor M does not move the switch W away from the normal position.

If it is desired to effect movement of the switch W from the normal position to the reverse position, this may be accomplished by first moving the switch control lever L from the reverse position to the normal position and then returning it to the reverse position.

On movement of the switch control lever L to the normal position contact 46 engages contact 55 and thereby establishes a circuit from terminal B of battery 25 to control wire 50, this circuit including wire 58, winding of relay LKR, wire 56, contacts 55-46 and wire 50. At this time the contact 51 of relay RWR is released and engages contact 76 which is connected to contact 77 of lock relay LR. When the contacts of relay LR become picked up, contact 77 engages contact 78 to thereby connect wire 50 to wire 79 which is connected to one terminal of the winding of the relay NWR. The other terminal of the winding of relay NWR has connected thereto wire 30 leading to normal polar contact 28 of relay WP which contact is engaged at this

time by polar contact 20 to which is connected common wire 24 leading to terminal C of battery 25. It will be seen, therefore, that on movement of the switch control lever L to the normal position the winding of relay NWR is energized and the contacts of this relay become picked up.

As the switch W is assumed to be in the normal position, the switch operated contact 114 interrupts the circuit of the switch motor M so that energization of the winding of relay NWR does not effect operation of the switch motor M.

However, upon picking up of the contacts of relay NWR contact 43 engages contact 41 to thereby complete a circuit from wire 39, to wire 40 leading to a terminal of relay WRP, the other terminal of which has connected thereto wire 16 leading from terminal C of battery 15. The winding of relay WRP is energized, therefore, and its contact 36 is picked up and establishes a connection from wire 30, leading from normal polar contact 28 of relay WP, to wire 33 leading to a terminal of relay RWR.

On subsequent movement of the switch control lever L from the normal to the reverse position a circuit is established to energize the winding of the relay RWR, while the circuit for energizing the winding of relay NWR is interrupted.

This circuit is traced from terminal B of battery 25 through wire 58, winding of relay LKR, wire 56, lever contacts 65-47, control wire 52, contacts 53-85 of relay NWR, wire 86, contacts 37-89 of lock relay LR, wire 99, winding of relay RWR, wire 33, contacts 36-35 of relay WRP, wire 30, normal polar contacts 28-20 of relay WP and common wire 24 to terminal C of battery 25.

On picking up of the contacts of relay RWR a circuit is established to energize the switch motor M to cause it to move the switch W from the normal to the reverse position, as previously explained in detail.

In like manner, if when the control lever L and the switch W are in the reverse position and the lock relay LR is released, the switch control lever L is moved from the reverse to the normal position, no change will occur in the position of the switch on subsequent energization of the lock relay LR.

When the lock relay LR is deenergized, the relays RWR and NWR are both deenergized, as previously explained, while the relay WRP is also deenergized with the result that its contact 36 is released.

When the switch W is in the reverse position, 55 the switch operated contacts 10 and 11 establish a circuit to supply current of reverse polarity to the winding of the polarized switch control relay WP with the result that the polar contacts of this relay are in their reverse positions, while the neutral contacts of the relay are picked up.

On movement of the switch control lever L from the reverse to the normal position the lever operated contact 46 engages contact 55 and thus establishes the circuit from terminal B of battery 25 to control wire 50. At this time, since relay RWR is deenergized, its contact 51 engages contact 76, but as contact 77 of lock relay LR is released, no circuit is established to the winding of relay NWR. The relay NWR will remain deenergized, therefore, and will not establish an energizing circuit for the switch motor M.

The energizing circuit for the winding of relay NWR will not be established when the lock relay LR becomes energized and its contacts are picked up. When contact 77 picks up and engages con-

tact 78, a circuit is established from wire 50 to one terminal of the winding of the relay NWR. The other terminal of the winding of the relay NWR has connected thereto wire 39 leading to the normal polar contact 28 of relay WP. However, at this time polar contact 20 is in its reverse position and does not engage contact 28 so that no circuit is established from contact 28 and wire 30 to the common wire 24.

In addition, as previously stated, contact 36 of relay WRP is released so that a circuit is not established from wire 30 to wire 33 leading to the reverse polar contact 32 of relay WP. It will be seen, therefore, that the circuit of the winding of the relay NWR is interrupted and that the winding does not become energized on picking up of the contacts of lock relay LR.

If it is desired to effect movement of the switch W from the reverse to the normal position, it may be accomplished by returning the switch control lever L to the reverse position and thereafter moving it to the normal position.

On movement of the switch control lever L to the reverse position a circuit is established to energize the winding of the switch control relay RWR. This circuit is traced from terminal B of battery 25 through wire 58, winding of relay LKR, wire 56, lever contacts 65-47, control wire 52, contacts 53-85 of relay NWR, wire 86, contacts 37-89 of lock relay LR, wire 99, winding of relay RWR, wire 33, reverse polar contacts 32-20 of relay WP and common wire 24 to terminal C of battery 25.

On energization of the winding of relay RWR its contact 44 is picked up, thereby completing 35 the circuit for energizing the winding of relay WRP with the result that contact 36 of this relay is picked up and completes the circuit between wires 33 and 30.

On subsequent movement of the switch control lever L from the reverse to the normal position a circuit is established to energize the winding of the relay NWR, while the previously traced circuit for energizing the winding of relay RWR is interrupted.

The circuit for energizing the winding of relay NWR is traced from terminal B of battery 25 through wire 58, winding of relay LKR, wire 56, contacts 55-46, control wire 50, contacts 51-76 of relay RWR, contacts 77-78 of lock relay LR, wire 79, winding of relay NWR, wire 39, contacts 35-36 of relay WRP, wire 33, reverse polar contact 32-20 of relay WP and neutral wire 24 to terminal C of battery 25.

On picking up of the contacts of relay NWR 55 a circuit is established to energize the switch motor M to cause it to move the switch W from the reverse to the normal position in the manner heretofore described in detail.

This system is also arranged so that storage 60 of switch control will be prevented while the lock relay LR is deenergized even though the switch W creeps and one of the switch control relays is energized to effect return of the switch to the position from which it moved.

When the lock relay LR is deenergized contact 92 is released and interrupts the connection from wire 14, leading from terminal B of battery 15, to wire 39, while contact 92 connects wire 14 to wire 94. Wire 94 is connected by polar contact 97 of relay WP to wire 99 or wire 104, depending upon the position occupied by the contact, and it is through these circuits current is supplied to energize the switch control relays in the event the switch creeps. As contact 92 does not con- 75

nect wire 14 to wire 39, on picking up of the contacts of one of the switch control relays and resultant establishment of a circuit from wire 39 to wire 40, the winding of relay WRP is not energized and contact 36 remains released.

If the lock relay LR should become energized at a time when one of the switch control relays is energized as a result of creeping of the switch, the contact 92 of relay LR will become picked up and will interrupt the circuit for energizing the switch control relay and the contacts of the switch control relay will become released and will interrupt connection from wire 39 to wire 40.

On picking up of the contact 92 of relay LR it engages contact 45 and establishes connection from wire 14 to wire 39. The connection from wire 14 to wire 38 by contact 92 of relay LR may be established before connection of wire 39 to wire 40 is interrupted by the contact of the switch control relay. However, this overlapping will be momentary only and the contact of the switch control relay will become released before the winding of relay WRP has been energized long enough to cause the contact 36 to become picked up. Contact 36, therefore, will not establish a circuit between wires 39 and 33, and if the switch control lever L is out of correspondence with the switch W, and therefore out of correspondence with the polar contacts of the relay WP, a circuit will not be established to energize one of the switch control relays and the motor M will not be energized to move the switch W.

If the operator desires to effect movement of the switch he may do so by returning the control lever to a position in correspondence with the switch and the switch repeating relay. This will establish a circuit to energize one of the switch control relays, and when the contacts of this relay become picked up a circuit is established to energize the winding of relay WRP so that contact 36 becomes picked up.

From the foregoing it will be seen that the system shown in Fig. 1 of the drawing provides means employing two control wires and a neutral wire to selectively control the motor for operating the track switch, and for also providing at the control point an indication as to whether or not the switch is locked, and also whether or not the switch and the switch control lever are in correspondence.

In Fig. 2 of the drawing I have shown a modified form of system in which indications are given as to the position occupied by the switch. In the system shown in Fig. 2 indication lamps are provided which are controlled in such a manner that upon movement of the switch control lever to either of its positions, and on subsequent movement of the switch to the corresponding position, a lamp is illuminated to indicate that the switch has attained the position corresponding to the position of the control lever.

The system shown in Fig. 2 of the drawing is the same as that shown in Fig. 1 of the drawing except for some of the apparatus at the control point, as will be explained in detail below, and the same reference characters are employed in Fig. 2 of the drawing as are employed in Fig. 1 of the drawing to indicate elements which are common to the two systems.

The modification shown in Fig. 2 of the drawing does not employ the relay WKR and the transit light TL which are employed in the system shown in Fig. 1. Instead the modification shown in Fig. 2 has a normal indication relay

NWK, a reverse indication relay RWK, and normal and reverse indication lamps NL and RL.

One terminal of the winding of the relay NWK is connected by a wire 141 to contact 69 which is engaged by lever contact 47 in the normal position of the switch control lever L. The other terminal of the winding of the relay NWK has a branch of the wire 62 connected thereto, while the relay NWK has a contact 143 which is constantly connected to wire 58 leading to terminal B of battery 25. The contact 143 when picked up establishes a circuit to illuminate the normal indication lamp NL.

One terminal of the winding of the reverse indication relay RWK is connected by a wire 145 to the contact 64 which is engaged by lever contact 46 in the reverse position of the switch control lever L. The other terminal of the winding of the relay RWK has connected thereto a branch of the wire 62 leading from the terminal C of battery 25. The relay RWK has a contact 146 which has connected thereto a branch of the wire 58 leading from terminal B of battery 25, while the contact when picked up completes a circuit to illuminate the reverse indication lamp RL.

The circuits for energizing the winding of the relay LKR are the same as described in detail in connection with the system shown in Fig. 1 of the drawing. The relay LKR has a movable contact 66 which has constantly connected thereto a branch of the wire 58 leading from terminal B of the battery 25, while the contact 66 when released establishes a circuit to illuminate lock lamp LL.

In the operation of the modification shown in Fig. 2 the relay LKR is controlled in the manner described in detail in connection with the system shown in Fig. 1 of the drawing. As long as the lock relay LR is energized, the winding of the relay LKR is energized in series with the winding of one or the other of the switch control relays NWR or RWR depending upon the position of the switch control lever L. As long as the winding of the relay LKR is energized, its contact 66 is picked up and interrupts the circuit for the lamp LL.

In the event, however, that the lock relay LR becomes deenergized the energizing circuit for the winding of the relay LKR is interrupted and the contact 66 is released and thereby completes the circuit to the lamp LL which is thereupon illuminated to indicate that the switch W is locked and that its position cannot be changed.

When the switch control lever L is in the normal position, as shown in Fig. 2 of the drawing, the winding of the relay NWK is energized by current supplied from the battery 15 in the manner explained in detail below. At this time the switch W is in the normal position, the switch control relay NWR is energized and the polarized relay WP is energized in the normal direction.

As a result, when the switch W is in the normal position the winding of the relay NWK is energized by current supplied from the battery 15 over a circuit which is traced from terminal B of the battery (see Fig. 1 of the drawing), through wire 14, neutral contacts 89-85 of relay WP, normal polar contacts 84-83 of relay WP, wire 82, contacts 81-53 of relay NWR, control wire 52, lever contacts 47-60, wire 141, winding of relay NWK and wire 62 to common wire 24 which is connected by wire 16 to terminal C of battery 15.

As the winding of relay NWK is energized, contact 143 is picked up and establishes the circuit

to energize the lamp NL to indicate that the switch W is in the normal position.

In this position of the switch control lever L the contact 46 does not engage stationary contact 64 and the circuit of the winding of the relay RWK, therefore, is interrupted and the contact 146 is released with the result that lamp RL is not lighted.

In similar manner, when the switch control relay L is in the reverse position, the relay RWK is energized and the relay NWK is deenergized, while the lamp RL is lighted and the lamp NL is extinguished.

When the control lever L is moved to the reverse position, the previously traced circuit for energizing the winding of the relay NWK is interrupted, while a circuit is established to energize the winding of relay RWK.

When the switch control lever L is moved to the reverse position, a circuit is established to energize the relay RWR, and when the switch W attains the reverse position, the relay WP is energized with current of reverse polarity as explained in detail in connection with the system shown in Fig. 1 of the drawing.

In this position of the switch control lever L the winding of the relay RWK is energized over a circuit which is traced from terminal B of battery 15 (see Fig. 1), wire 14, neutral contacts 88-85 of relay WP, reverse polar contacts 74-71 of relay WP, wire 73, contacts 72-51 of relay RWR, control wire 58, lever contacts 66-64, wire 145, winding of relay RWK, wire 62 to common wire 24 which is connected by wire 16 to terminal C of battery 15.

As the winding of relay RWK is energized, its contact 146 is picked up and establishes the circuit to energize the reverse lamp RL which is illuminated to indicate that the switch W occupies the reverse position.

Although I have herein shown and described only two forms of the improved switch control and indication system embodying my invention, it is understood that various changes and modifications may be made therein within the scope of the appended claims without departing from the spirit and scope of my invention.

Having thus described my invention, what I claim is:

1. In combination, a railway track switch, a motor for moving the switch between a normal and a reverse position, a first, a second and a third conductor, a control member movable between a normal and a reverse position, a first and a second source of current, the control member being operable in its normal position to connect the first source of current to the first and second conductors and being operable in its reverse position to connect the first source of current to the first and third conductors, a normal control device energized from the first and second conductors and operable when energized to effect operation of the motor to cause it to move the switch to the normal position, a reverse control device energized from the first and third conductors and operable when energized to effect operation of the motor to cause it to move the switch to the reverse position, switch indication means operable when energized to provide one indication of the condition of the switch and operable when deenergized to provide a different indication of the condition of the switch, the control member being operable in the normal position to connect the indication means to the first and third conductors and being operable in

the reverse position to connect the indication means to the first and second conductors, a second source of current, and means controlled by and actuated in accordance with the position of the switch, said means being operable only in the normal position of the switch to connect said second source of current to the first and third conductors and being operable only in the reverse position of the switch to connect said second source of current to the first and second conductors.

2. In combination, a railway track switch, a motor for moving the switch between a normal and a reverse position, a normal control device operable when energized to effect movement of the switch to the normal position, a reverse control device operable when energized to effect movement of the switch to the reverse position, a first, a second and a third conductor, a control member movable between a normal and a reverse position, a source of current, the control member being operable in its normal position to connect the source of current to the first and second conductors and being operable in the reverse position to connect the source of current to the first and third conductors, means controlled by and actuated in accordance with the position of the switch, said means being operable when the switch is in one position to establish a circuit to connect the first conductor to one of said control devices and being operable when the switch is in the other position to establish a circuit to connect the first conductor to the other of said control devices, a circuit controlled by the reverse control device for connecting the second conductor to the normal control device, and a circuit controlled by the normal control device for connecting the third conductor to the reverse control device.

3. In combination, a railway track switch, a motor for moving the switch between a normal and a reverse position, a normal control device operable when energized to effect movement of the switch to the normal position, a reverse control device operable when energized to effect movement of the switch to the reverse position, a first, a second and a third conductor, a control member movable between a normal and a reverse position, a source of current, the control member being operable in its normal position to connect the source of current to the first and second conductors and being operable in the reverse position to connect the source of current to the first and third conductors, means controlled by and actuated in accordance with the position of the switch, said means being operable when the switch is in one position to establish a circuit to connect the first conductor to one of said control devices and being operable when the switch is in the other position to establish a circuit to connect the first conductor to the other of said control devices, a circuit controlled by the reverse control device for connecting the second conductor to the normal control device, a circuit controlled by the normal control device for connecting the third conductor to the reverse control device, a slow acting relay controlled jointly by said normal and reverse control devices, and a circuit controlled by said relay and establishing connection between the circuits by means of which the said first conductor is connected to said normal and reverse control devices.

4. In combination, a railway track switch, a motor for moving the switch between a normal

and a reverse position, a normal control device operable when energized to effect movement of the switch to the normal position, a reverse control device operable when energized to effect movement of the switch to the reverse position, 5 a first, a second and a third conductor, a control member movable between a normal and a reverse position, a source of current, the control member being operable in its normal position to connect the source of current to the first and 10 second conductors and being operable in the reverse position to connect the source of current to the first and third conductors, means controlled by and actuated in accordance with the position of the switch, said means being operable when the switch is in the normal position to establish a circuit to connect the first conductor to the normal control device and being operable when the switch is in the reverse position to 15 establish a circuit to connect the first conductor to the reverse control device, a circuit controlled by the reverse control device for connecting the second conductor to the normal control device, a circuit controlled by the normal control device 20 for connecting the third conductor to the reverse control device, a slow acting relay controlled jointly by said normal and reverse control devices, and a circuit controlled by said relay and establishing connection between the circuits by means of which the said first conductor is 25 connected to said normal and reverse control devices.

5. In combination, a railway track switch, a motor for moving the switch between a normal and a reverse position, a normal control device operable when energized to effect movement of the switch to the normal position, a reverse control device operable when energized to effect movement of the switch to the reverse position, 40 a first, a second and a third conductor, a control member movable between a normal and a reverse position, a source of current, the control member being operable in its normal position to connect the source of current to the first and second conductors and being operable in the reverse position to connect the source of current to the first and third conductors, means controlled by and operated in accordance with the position of the switch, said means being operable when the switch is in one position to establish a circuit to connect the first conductor to one of said 45 control devices and being operable when the switch is in the other position to establish a circuit to connect the first conductor to the other of said control devices, a circuit controlled by the reverse control device for connecting the second conductor to the normal control device, a circuit controlled by the normal control device for connecting the third conductor to the reverse control device, and a lock relay controlled by traffic conditions in the vicinity of the said switch, said lock relay controlling the circuits for energizing the normal and reverse control devices.

6. In combination, a railway track switch, a motor for moving the switch between a normal and a reverse position, a normal control device operable when energized to effect movement of the switch to the normal position, a reverse control device operable when energized to effect movement of the switch to the reverse position, 45 a first, a second and a third conductor, a control member movable between a normal and a reverse position, a source of current, the control member being operable in its normal position to connect

the source of current to the first and second conductors and being operable in the reverse position to connect the source of current to the first and third conductors, means controlled by and operated in accordance with the position of the switch, said means being operable when the switch is in one position to establish a circuit to connect the first conductor to one of said control devices and being operable when the switch is in the other position to establish a circuit to connect the first conductor to the other of said control devices, a circuit controlled by the reverse control device for connecting the second conductor to the normal control device, a circuit controlled by the normal control device 50 for connecting the third conductor to the reverse control device, and a lock relay controlled by traffic conditions in the vicinity of the said switch, said relay controlling lock relay contacts when picked up establishing the circuits for energizing the normal and reverse control devices, each of said control devices having associated therewith a supply circuit controlled by said lock relay and by means of which said control device may be supplied with current, each 55 such supply circuit being controlled in accordance with the position of the switch and being completed when and only when the lock relay contacts are released and the switch moves away from the position to which the control device is energized by the said supply circuit is effective to cause movement of the switch.

7. In combination, a railway track switch, a motor for moving the switch between a normal and a reverse position, a normal control device 60 operable when energized to effect movement of the switch to the normal position, a reverse control device operable when energized to effect movement of the switch to the reverse position, a first, a second and a third conductor, a control member movable between a normal and a reverse position, a source of current, the control member being operable in its normal position to connect the source of current to the first and second conductors and being operable in the reverse position to connect the source of current to the first and third conductors, means controlled by and operated in accordance with the position of the switch, said means being operable when the switch is in one position to establish a circuit to connect the first conductor to one of said control devices and being operable when the switch is in the other position to establish a circuit to connect the first conductor to the other of said control devices, a circuit controlled by the reverse control device for connecting the second conductor to the normal control device, a circuit controlled by the normal control device for connecting the third conductor to the reverse control device, and a slow acting relay having a 65 movable element having a normal position and an operated position, said element being effective in its operated position to connect the first conductor to both the normal and the reverse control devices irrespective of the condition of the means controlled in accordance with the position of the switch, either of said control devices being operative when energized to effect movement of the relay element to the operated position.

8. In combination, a railway track switch, a motor for moving the switch between a normal and a reverse position, a first, a second and a third conductor, a first and a second source of current each having one terminal connected 70

to said first conductor, a control member movable between a normal and a reverse position, said control member being operable in the normal position to connect the other terminal of the first source of current to the second conductor and being operable in the reverse position to connect the other terminal of said first source of current to the third conductor, a normal control device energized from the first and second conductors and operable when energized to cause the motor to move the switch to the normal position, a reverse control device energized from the first and third conductors and operable when energized to cause the motor to move the switch to the reverse position, an element controlled by and actuated between a normal and a reverse position in accordance with movement of the switch, said element being operable in the normal position to connect the other terminal of the second source of current to the third conductor and being operable in the reverse position to connect the other terminal of said second source of current to said second conductor, and indication means operable when energized to provide an indication of the condition of the switch, said indication means being connected to said first conductor, the control member being operable in the normal position to connect the indication means to the third conductor and being operable in the reverse position to connect the indication means to the second conductor.

9. In combination, a railway track switch, a motor for moving the switch between a normal and a reverse position, a first, a second and a third conductor, a first and a second source of current each having one terminal connected to said first conductor, a control member movable between a normal and a reverse position, said control member being operable in the normal position to connect the other terminal of the first source of current to the second conductor and being operable in the reverse position to connect said other terminal of said first source of current to the third conductor, a normal control device energized from the first and second conductors and operable when energized to cause the motor to move the switch to the normal position, a reverse control device energized from the first and third conductors and operable when energized to cause the motor to move the switch to the reverse position, an element controlled by and actuated between a normal and a reverse position in accordance with movement of the switch, said element being operable in the normal position to connect the other terminal of the second source of current to the third conductor and being operable in the reverse position to connect the other terminal of said second source of current to said second conductor, a normal and a reverse indication means each operable when energized to provide an indication of the position occupied by the switch, each of said indication means being connected to said first conductor, the control member being operable in the normal position to connect the normal indication means to the third conductor and being operable in the reverse position to connect the reverse indication means to the second conductor.

10. In combination, a railway track switch, a motor for moving the switch between a normal and a reverse position, a first, a second and a third conductor, a first and a second source of current each having one terminal connected to said first conductor, a control member movable between a normal and a reverse position, said con-

trol member being operable in the normal position to connect the other terminal of the first source of current to the second conductor and being operable in the reverse position to connect said other terminal of said first source of current to the third conductor, a normal control device energized from the first and second conductors and operable when energized to cause the motor to move the switch to the normal position, a reverse control device energized from the first and third conductors and operable when energized to cause the motor to move the switch to the reverse position, an element controlled by and actuated between a normal and a reverse position in accordance with movement of the switch, a circuit controlled by the normal control device and by said element and operable when said element is in the normal position to connect said other terminal of said second source of current to said third conductor, a circuit controlled by the reverse control device and by said element and operable when said element is in the reverse position to connect said other terminal of said second source of current to said second conductor, and indication means operable when energized to provide an indication of the condition of the switch, said indication means being connected to said first conductor, the control member being operable in the normal position to connect the indication means to the third conductor and being operable in the reverse position to connect the indication means to the second conductor.

11. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second conductors and being operable in the reverse position to connect said source of current to the first and third conductors, an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, and means controlled jointly by said normal and reverse control devices for also establishing connection from said first conductor to said normal and reverse control devices.

12. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second

conductors and being operable in the reverse position to connect said source of current to the first and third conductors, and an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, the normal control device controlling connection of said third conductor with said reverse control device, and the reverse control device controlling connection of said second conductor with said normal control device.

13. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second conductors and being operable in the reverse position to connect said source of current to the first and third conductors, an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, the normal control device controlling connection of said third conductor with said reverse control device, the reverse control device controlling connection of said second conductor with said normal control device, and means controlled jointly by said normal and reverse control devices for also establishing connection from said first conductor to said normal and reverse control devices.

14. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second conductors and being operable in the reverse position to connect said source of current to the first and third conductors, an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, a second source of current, the normal control device controlling means to connect said second source of current to the first and third conductors, the reverse control device controlling means to connect the second source of current to the first and second conductors, and

trol device, and a slow acting relay controlled jointly by said control devices, said relay being operative when either one of said control devices is energized to establish a circuit to connect the first conductor to the other one of said control devices, said relay being operative on deenergization of a control device to interrupt such circuit only after a predetermined time interval.

15. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second conductors and being operable in the reverse position to connect said source of current to the first and third conductors, an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, a slow acting relay controlled jointly by said control devices, said relay being operative when either one of said control devices is energized to establish a circuit to connect the first conductor to the other one of said control devices, said relay being operative on deenergization of a control device to interrupt such circuit only after a predetermined time interval, and a lock relay responsive to traffic conditions in the vicinity of the switch and controlling both of said control devices.

16. In combination, a railway track switch, a motor for moving the switch between a normal and a reverse position, a first, a second and a third conductor, a normal control device energized from the first and second conductors and operable when energized to cause the motor to move the switch to the normal position, a reverse control device energized from the first and third conductors and being operable when energized to cause the motor to move the switch to the reverse position, a source of current, a control member movable between a normal and a reverse position, said member being operable in the normal position to connect said source of current to the first and second conductors and being operable in the reverse position to connect said source of current to the first and third conductors, an element controlled by and movable between a normal and a reverse position in accordance with movement of the switch, said element controlling connection of the first conductor with said control devices and being operable in its normal position to connect the first conductor to the normal control device and being operable in its reverse position to connect said first conductor to the reverse control device, a second source of current, the normal control device controlling means to connect said second source of current to the first and third conductors, the reverse control device controlling means to connect the second source of current to the first and second conductors, and

indication means operable when energized to provide an indication of the condition of the switch, the control member being operable in the normal position to connect the indication means to the 5 first and third conductors and being operable in the reverse position to connect the indication means to the first and second conductors.

17. In combination, a railway track switch, a motor for moving the switch between a normal 10 and a reverse position, a first, a second and a third conductor, a normal control device energized from the first and second conductors and operable when energized to cause the motor to move the switch to the normal position, a reverse 15 control device energized from the first and third conductors and being operable when energized to cause the motor to move the switch to the reverse position, a source of current, a control member movable between a normal and a reverse 20 position, said member being operable in the normal position to connect said source of current to the first and second conductors and being operable in the reverse position to connect said source of current to the first and third conductors, an element controlled by and movable 25 between a normal and a reverse position in accordance with movement of the switch, said element controlling connection of the first conductor with said control devices and being operable in its 30 normal position to connect the first conductor to the normal control device and being operable in its reverse position to connect said first conductor to the reverse control device, a lock relay responsive to traffic conditions in the vicinity of 35 said switch and controlling the circuits for energizing both of said control devices, an indication relay connected in series with the circuit by means of which one terminal of said source of current is connected to said second or third conductors, and switch indication means controlled 40 by said indication relay.

18. In combination, a railway track switch, a motor for moving the switch between a normal and a reverse position, a first, a second and a third conductor, a normal control device energized from the first and second conductors and operable when energized to cause the motor to move the switch to the normal position, a reverse 45 control device energized from the first and third conductors and operable when energized to cause the motor to move the switch to the reverse position, a first and a second source of current, indication means operable when energized to provide an indication of the condition of the 50 switch, a control member movable between a normal and a reverse position, said member being operable in the normal position to connect the first source of current to the first and second conductors and to also connect the indication means to the first and third conductors, said member being operable in the reverse position to connect the first source of current to the first and third conductors and to also connect the indication 55 means to the first and second conductors, an element controlled by and movable between a normal and a reverse position in accordance with movement of the switch, said element controlling connection of the first conductor with said control devices and also controlling connection of 60 said second source of current to said conductors, said element being operable in the normal position to connect said second source of current to the first and third conductors and being operable in the reverse position to connect said second 65 source of current to said conductors, said element being operable in the normal position to connect said second source of current to the first and third conductors and being operable in the reverse position to connect said second 70 source of current to said conductors, said element being operable in the normal position to connect said second source of current to the first and third conductors and being operable in the reverse position to connect said second 75 source of current to said conductors.

source of current to the first and second conductors.

19. In combination, a railway track switch, a motor for moving said switch between a normal and a reverse position, an electroresponsive control device having a first condition in which it causes the motor to move the switch to the normal position and having a second condition in which it causes the motor to move the switch to the reverse position, said control device also having a third condition in which it prevents operation of the motor, a manually controlled member movable between a normal and a reverse position, said member being operable in the normal position to establish a circuit through which current may be supplied to the control device to cause said device to assume its first condition, said member being operable in the reverse position to establish a circuit through which current may be supplied to said control device to cause said device to assume its second condition, means controlled by the switch and controlling energization of said control device by current supplied as a result of operation of the manually controlled member, said switch controlled means being operable when and only when the switch is in the normal position to permit energization of said control device only to cause said device to assume its first condition and being operable when and only when the switch is in its reverse position to permit energization of said control device only to cause said device to assume its second condition, and means controlled by said control device and also controlling energization of said device by current supplied as a result of 35 operation of said manually controlled member, said means being operable when said control device is in either its first or second condition to establish a circuit to permit energization of said control device by current supplied through the 40 circuits controlled by said manually controlled member to cause said device to assume the other one of said first or second conditions, said means being operable to maintain said circuit for a predetermined time interval after said control device assumes its third condition, whereby on a change in the position of the manually controlled member a circuit is maintained to effect a corresponding change in the condition of the said control device provided the change in the 45 condition of the control device is completed promptly.

20. In combination, a railway track switch, a motor for moving said switch between a normal and a reverse position, a first relay operable when energized to condition the motor to move the switch to the normal position, a second relay operable when energized to condition the motor to move the switch to the reverse position, a manually controlled member movable between 55 a normal and a reverse position, said member being operable in the normal position to establish a circuit through which current may be supplied to energize the first relay and being operable in the reverse position to establish a circuit through which current may be supplied to energize the second relay, means controlled by the switch and controlling energization of said first and second relays by current supplied as a result of movement of said manually controlled member, said means being operative when and only when the switch is in the normal position to establish only the circuit for energizing the first relay and being operative when and only when the switch is in the reverse position to 65 70 75

establish only the circuit for energizing the second relay, and a slow acting relay controlled by said first and second relays, said slow acting relay also controlling energization of said first and second relays by current supplied as a result 5 of movement of said manually controlled member, said slow acting relay being operable when the first relay is energized to establish a circuit to permit energization of the second relay and being operable when the second relay is energized 10 to establish a circuit to permit energization of the first relay, said slow acting relay being operable to maintain the circuit established by said slow acting relay for a time interval subsequent to the release of the first or second relay, 15 whereby on a change in the position of the manually controlled member a circuit is established to energize the deenergized one of the first and second relays provided energization of such 20 relay is effected within a predetermined time subsequent to deenergization of the energized one of the said relays.

21. In combination, a railway track switch, a motor for moving said switch between a normal 25 and a reverse position, a first control relay operable when energized to condition the motor to move the switch to the normal position, a second control relay operable when energized to condition the motor to move the switch to the reverse position, a first, a second and a third conductor, 30 a first and a second source of current each having one terminal connected to said first conductor, a first indication relay having one terminal of its winding connected to said first conductor, a second indication relay having one terminal of its winding connected to the other terminal 35 of said first source of current, a manually controlled member movable between a normal

and a reverse position, said member being operable in the normal position to connect the other terminal of the winding of the first indication relay to the second conductor and to connect the other terminal of the second indication relay to the third conductor, said member being operable in the reverse position to connect the other terminal of the first indication relay to the third conductor and to connect the other terminal of the second indication relay to the second conductor, means operable when and only when the switch is in the normal position to establish connection from the first conductor to one terminal of the winding of the first control relay and to establish a circuit through which connection may be established from the other terminal of the second source of current to the third conductor, means operable when and only when the switch is in the reverse position to establish connection from the first conductor to one terminal 10 of the winding of the second control relay and to establish a circuit through which connection may be established from the other terminal of the second source of current to the second conductor, means controlled by the second control relay for 15 establishing connection from the second conductor to the other terminal of the winding of the first control relay, means controlled by the first control relay for establishing connection from the third conductor to the other terminal of the second control relay, means controlled jointly by said control relays for establishing connection from the first conductor to the windings of said control relays, and means controlled jointly by said indication relays for indicating the condition 20 of the switch. 25 30 35

HENRY S. YOUNG.

CERTIFICATE OF CORRECTION.

Patent No. 2,177,125.

October 24, 1939.

HENRY S. YOUNG.

It is hereby certified that error appears in the printed specification of the above numbered patent requiring correction as follows: Page 11, second column, line 19, claim 6, strike out the words relay controlling; and that the said Letters Patent should be read with this correction therein that the same may conform to the record of the case in the Patent Office.

Signed and sealed this 5th day of December, A. D. 1939.

(Seal)

Henry Van Arsdale,
Acting Commissioner of Patents.
